UNITED STATES PATENT OFFICE.

CLAUDE RORABECK, OF DAYTON, OHIO.

OIL-PUMP FOR DIESEL ENGINES.

1,132,797.

Specification of Letters Patent. Patented Mar. 23, 1915.

Application filed April 19, 1913. Serial No. 762,301.

To all whom it may concern:

Be it known that I, CLAUDE RORABECK, citizen of the United States, residing at Dayton, in the county of Montgomery and State of Ohio, have invented certain new and useful Improvements in Oil-Pumps for Diesel Engines; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 This invention relates to improvements in injection oil pumps for constant pressure oil engines.

The object of the invention is to provide an oil pump which is capable of delivering 20 to the cylinders of the engine varying quantities of oil at the times of the initial injection thereof. The oil starts to inject into the cylinder at the right time and the quantity is regulated by a valve which is controlled by a governor. Heretofore, it has been the custom to inject the oil into the injection compressed air before the compressed air valve opened up. In this case it was not required to time the oil injection as accurately as is necessary with my type of fuel 25 valve and pump, which differs from the principles involved in other types of fuel valves and pumps.

The fuel valve which is applicable to the 30 present invention is described in my co-pending application, Serial No. 738,227, filed December 23, 1912.

Another object of said invention is to provide a pump which is simple in construction 40 and efficient in its operation.

Referring to the accompanying drawings, Figure 1 is a front elevation of my improved pump, the same being a section on the line $a-a$ of Fig. 2; Fig. 2 is a section thereof approximately on the line $b-b$ of Fig. 1; Fig. 3 is a top plan view of the actuating levers for the inlet valves; Fig. 4 is a side elevation of the same, partially in section; Fig. 5 is a section on the line $c-c$ of Fig. 1; Fig. 6 is a section on the line $d-d$ of Fig. 2; Fig. 7 is a section on line $e-e$ of Fig. 2;

and Fig. 8 is a detail view of the driving gear and ratchet for the pump.

In the specification and drawings, similar reference characters indicate corresponding parts.

Referring more particularly to the drawings, 1 represents a hollow base member, the lower interior portion of which forms an oil reservoir. The reservoir is fed with oil by supply pumps, the cylinders 2 of which may be integral parts of the base member 1 as is shown in the drawings. The cylinders 2 are provided with plungers 3 which extend from cross-heads 4. Mounted in the cross-heads 4 are sliding blocks 5 which receive crank pins 6 on a drive shaft 7 journaled in bearings 8 in the base member 1. The said shaft 7 and the plungers 3 connected thereto are driven from the crank or cam shaft of the engine (not shown) through a gear 9 freely mounted on said shaft 7. The gear 9 and shaft 7 are connected by a ratchet tooth 10 and pawl 11, which enables the shaft 7 to be actuated independently of the engine and gear 9 by a crank 12. The supply pumps are provided with inlet valves 13 which receive inlet pipes 14 extending from the main supply tank, and with exhaust valves 15 discharging into the reservoir in the bottom of the hollow base member 1. The base member 1 is provided with overflow walls 16 in one corner thereof which form a pocket 17. The pocket 17 is provided with a discharge pipe 18 which leads to the main supply tank. The height of the walls 16 regulates the height of the oil in the reservoir, and as the capacity of the supply pumps is greater than the demands of the engine cylinders, the excess of oil constantly overflows the walls 16 and returns to the main supply tank, thereby maintaining a constant level in the reservoir.

The oil is fed to the engine cylinders, from pumps provided with plungers 17 extending from the cross-heads 4, through stuffing glands 18 and into pump chambers 19 in a chambered member 20. The inlet to the chambers 19 is controlled by combined inlet and regulating valves 21 the stems 26 of which extend through packing glands 22. The outlets from the chambers 19 are con-

trolled by check valves 23 which communicate with the chambers 19 through passageways 24 and which are provided with outlet pipes 25 leading to the inlet valves of the engine cylinders. The inlet to the chambers 19 from the reservoir in the base 1 is through a suction pipe 27 the lower end of which lies within the oil in the reservoir. The upper end of the pipe 27 is mounted in 10 the chambered member 20, and said pipe communicates with a passageway 29 in the chambered member 20 through a valve 21^a. The valve 21^a is instrumental in shutting off the supply of oil to the chambers 19 thus 15 preventing the oil being fed to the cylinders. The passageways 29 communicate with the chambers 19 through annular recesses 30 and ports 31. The valves 21 are opened during the downward or suction 20 stroke of the plungers 17 to admit the oil into the chambers 19, and are opened during the upward stroke of the plungers to regulate the amount of oil fed to the engine cylinders. The stems 26 of the valves 21 25 extend through guides 32 and are provided with collars 33 between which and the guides 32 springs 34 are mounted. The springs 34 are instrumental in maintaining the valves 21 on their seats against the pressure of the oil when it is being delivered by the plungers 17. Mounted on the upper ends of the stems 26 are collar nuts 35 which are rigidly secured in adjusted positions by jam nuts 36. Adapted to engage the under 30 sides of the collars 35 are the bifurcated ends of levers 37 the opposite ends of which are pivotally connected at 38 to the upper ends of connecting rods 39. The levers 37 are provided with projections 40 forming 35 fulcrums for said levers which turn upon the heads 41 of screws 42 adjustably mounted in the guides 32. The ends of the connecting rods 39 opposite the pivots 38 are pivotally connected to lugs 42^a on the cross-heads 4, said levers 37, are, therefore, actuated by the plungers 17. When the plungers 17 descend, the levers 37 elevate 40 the valves 21 thereby permitting the fuel oil to be drawn into the chambers 19. When 45 said plungers 17 ascend, they initially inject the oil into the cylinders, and said point of injection will always be at the same time relative to the stroke of the engine pistons. During the subsequent upward movement 50 of the plungers 17, the valves 21 are opened to regulate the amount of oil injected into the engine cylinders. The point at which the valves are opened, during the delivery 55 stroke of the plungers 17, and the amount of oil injected in the cylinders are controlled by a governor which maintains a constant speed of the engine.

Pivotally connected at 38 to the upper ends of the rods 39 are the ends of levers 60 43, which are actuated by the plungers 17.

The other ends of said levers 43 are fulcrumed on pivot pins 44, therefore, are of a different class from levers 37. The said levers 43 are provided with projections 45 at points intermediate their lengths which are adapted to engage the collar nuts 35. As the points of contact between the collar nuts 35 and the projections 45 lie between the pivots 38 and the fulcrums 44, the valves 21 will be elevated by the levers 43 during 10 the upward stroke of the plungers 17, and the time at which the projections 45 engage the collar nuts 35 to open the valves 21 will be regulated by the positions of the fulcrum pins 44. The fulcrum pins 44 are eccentrically mounted on a rocking member 46 journaled in a bearing 47. Attached to one of the pins 44 is a crank 48 which is connected to a governor or other speed regulating device, by a connecting rod 49. When 20 the speed of the engine increases, the fulcrum pins 44 are elevated and the valves 21 are elevated early in the delivery stroke of the plungers 17, thus permitting a small amount of oil to be delivered to the cylinders and a larger amount of oil to be returned to the reservoir through the port 31, thereby decreasing the speed of the engine. When the speed of the engine decreases, the fulcrum pins 44 are depressed and valves 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560

While in the drawings, I have shown the device as constructed in duplex form and adapted to supply oil to a double cylinder engine, I wish it to be understood that the 40 said device may be constructed for a single cylinder engine or an engine having any number of cylinders.

Without limiting myself to the precise arrangement shown and described which may 45 be varied within the scope of the claims, I claim—

1. In a pump of the type specified, a cylinder, a piston therein, a discharge valve, a combined inlet and regulating valve, a lever 50 actuated by said piston to positively open said combined inlet and regulating valve during the entire suction stroke of the piston, and a lever subject to variable movement and actuated by said piston to open 55 the combined inlet and regulating valve during the discharge stroke of the piston, substantially as specified.

2. In a pump of the type specified, the combination of a pump chamber having a piston therein and a discharge valve, of a combined inlet and regulating valve, a lever adapted to positively actuate said combined inlet and regulating valve during the suction stroke of the piston, and another lever 65

of a different class from said first named lever having an adjustable fulcrum and adapted to positively and variably open said combined inlet and regulating valve during 5 the latter part of the discharge stroke of the piston, said levers being actuated by the piston, substantially as specified.

In testimony whereof I affix my signature, in presence of two witnesses.

CLAUDE RORABECK.
